(57) **CLAIM**

The ornamental design for a low friction extended boot eyelet, as shown and described.

DESCRIPTION

FIG. 1 is a top perspective view of a low friction extended boot eyelet, showing my new design, shown in the environmental use in a reduced scale;

FIG. 2 is a top perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken line portions of FIG. 1 are included to show unclaimed environmental subject matter only and form no part of the claimed design.
